J. F. O'CONNOR.
SIDE BEARING PRESSURE EQUALIZER,
APPLICATION FILED NOV. 30, 1914.

1,175,374.

Patented Mar. 14, 1916.

Fig. 1

UNITED STATES PATENT OFFICE

JOHN F. O'CONNOR, OF CHICAGO, ILLINOIS, ASSIGNOR TO WILLIAM H. MINER, OF CHAZY, NEW YORK.

SIDE-BEARING-PRESSURE EQUALIZER.

1,175,374.

Specification of Letters Patent. Patented Mar. 14, 1916.

Application filed November 30, 1914. Serial No. 874,692.

To all whom it may concern:

Be it known that I, JOHN F. O'CONNOR, a citizen of the United States, residing at Chicago, in the county of Cook and State 5 of Illinois, have invented a certain new and useful Improvement in Side-Bearing-Pressure Equalizers, of which the following is a full, clear, concise, and exact description, reference being had to the accompanying drawings, forming a part of this specification.

This invention relates to improvements in side bearing pressure equalizers.

In the operation of railway cars, it is 15 found that the wear on the center plates between the body bolsters and truck bolsters sometimes causes the elimination of clearance between the side bearing members of the bolsters, with the result that a permanent load is supported by the side bearings, causing binding when the cars are on curved tracks and also resulting in excessive wear and destruction of the side bearing members.

25 The object of this invention is to provide means which, when such excessive wear has occurred, are automatically operated by the weight of the car itself to limit the maximum load to which the side bearing can be subjected, to a predetermined proportion of the total weight on one set of bolsters, until such time when proper adjustment of parts and clearance is again provided.

In the drawing forming a part of this 35 specification, Figure 1 is a part end elevation, part vertical section of a body and truck bolster of a car showing my improvements in connection therewith and Fig. 2 is a horizontal sectional view taken substantially on the line 2—2 of Fig. 1.

In said drawing, 10 denotes a body bolster and 11 a truck bolster, which are or may be of any suitable or well known form. The body bolster 10 has secured thereto on 45 the under side at the center, a center bearing plate 12 which fits within a suitably shaped recess 13 in the top face of the truck bolster center bearing plate 14. The latter is provided with a depending portion 15 which fits within a depending annular flange 16 formed preferably integrally with the top wall of the truck bolster 11. A king pin 17 is employed, 50 swivelly connecting the parts and extending through perforations in the body bolster 10,

plate 12 and plate 14. On each side of the king pin, the body bolster 10 is provided with an integral depending side bearing member 18 and the truck bolster is provided with an integral perforated boss 19 60 in which is slidably mounted a truck bolster side bearing member 20, the latter being in the form of an enlarged pin having a head 21 which is engaged by the under face of the depending members 18. The side walls 65 21 of the truck bolster 11, on their inner sides, are each provided with a pair of inwardly extending, integral perforated bosses 22, which are located intermediate the center of the truck bolster and the side 70 bearings. These bosses 22 are arranged in pairs, as clearly indicated in Fig. 2 and are adapted to receive therethrough heavy pins 23, the latter being headed at one end and held from accidental displacement by 75 means of cotters 24. Pivotedly mounted on each of the pins 23, is a lever 25 of the first class, said lever having an outwardly extending arm 26 which engages the lower end of a member 20. On the opposite side 80 of this pivot, the lever 25 is provided with a pair of inwardly extending, spaced lever arms 27—27 which engage the under side of the depending hub 15 of the center bearing plate 14.

As clearly appear from Fig. 2, the levers 85 25 are duplicates of each other to thereby facilitate and cheapen the manufacture. At its lower ends, the depending portion 15 is provided with an annular groove 28 adapted 90 to receive a collar formed by two semi-annular members 29—29 held together by bolts 30 passed through flanges 31—31 formed on said members 29. The side walls 21 of the truck bolster are cut away or recessed, as indicated at 32, to facilitate the application or removal of the collar above described.

The operation of the device is as follows: Upon pressure being applied to either of the movable side bearing members 20, the 100 load is transmitted to the lever 25 and should this pressure equal or exceed the predetermined proportion of total, there will result a movement of the lever and a lifting of the center plate 14 relative to the truck 105 bolster. In actual practice, the relative lengths of the arms 26 and 27 of the levers will be designed to suit requirements of the particular equipment. If the pressure on the side bearing be excessive, as would be due 110

to oscillation of the car body when moved around a curve under too high a speed, the temporary load is taken directly on the end of the bolster, the side bearing flange coming in contact with the top of collar 19 on truck bolster.

Although I have herein shown and described one form of my invention, the same is merely illustrative and I contemplate all changes and modifications that fall within the scope of the claims appended hereto.

I claim:

1. The combination with a body bolster and a truck bolster, of slideable side bearing members mounted in the truck bolster, and movable means operated upon downward movement of said members to elevate the body bolster at the center.
2. In a device of the character described, the combination with a body bolster and truck bolster pivotally connected, of vertically slideable side bearing members mounted in the truck bolster, and pivotally-mounted levers operated by said side bearing members to elevate the body bolster when pressure is applied to said members.
3. In a railway car, the combination with

a hollow truck bolster having a center bearing plate vertically movably mounted therein, of a body bolster having a center bearing plate coöperable with the first named center bearing plate, movably mounted side bearing members on the truck bolster, and pressure transmitting means between the movable side bearing members and the center bearing plate on the body bolster, said means including levers pivotally mounted within the truck bolster.

4. In a railway car, the combination with a truck bolster having a center bearing plate vertically movably mounted therein, of a body bolster having a center bearing plate coöperable with the first named center bearing plate, side bearing members mounted on said truck bolster and movable relatively thereto, and means, separate from said side bearing members, for transmitting downward pressure on said members to an upward pressure against the under side of the center bearing plate of the truck bolster.

JOHN F. O'CONNOR.
